REVERSIBLE ROTARY PUMP

Lon Shannon, Gold Beach, Oreg., assignor to
 Essaness Patents, Gold Beach, Oreg., a business
 trust

Application November 15, 1946, Serial No. 710,151

2 Claims. (Cl. 103—3)

1

My present invention relates to an improved reversible rotary pump and more particularly to a reversible type vaned impeller pump in which the direction of flow of fluid therethrough may be reversed without change in the direction of rotary movement of the impeller shaft. Generally the pump of my invention comprises a housing enclosing an adjustable impeller case which is movable vertically in the housing eccentrically of the impeller so that the vanes of the impeller direct a flow of liquid through the pump depending upon the position of the case.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a side elevational view of the pump of my invention shown operably connected with a motor.

Figure 2 is a top plan view of the pump.

Figure 3 is a vertical sectional view through the pump.

Figure 4 is a horizontal sectional view of the pump.

Figure 5 is a front elevational view of the pump with the cover removed the vanes being positioned for flow of liquid from left to right.

Figure 6 is a front elevational view of the pump with the cover and impeller removed.

Figure 7 is a view similar to Figure 5 but with the vanes positioned for flow from right to left.

Figure 8 is a similar view with the vanes in neutral or inoperative condition.

Figure 9 is a vertical sectional view through the housing.

Referring now to the drawings in detail I have illustrated the pump of my invention as operated by a motor 2 through shaft 4 and coupling 6 to pump shaft 8. A flange 10 enclosing packing 12 receives packing nut 14 and the shaft 8 is supported in the bearing 16 in the housing 18. This housing is provided with passages 20 and 22 for the pipes 24 and 26 respectively. The housing is supported upon the base 28, and a ring 30 forming a pump housing in which a rotor chamber is provided is secured to the front of the housing by bolts 32.

A cover plate 33 for the ring may be secured by bolts 35. Within the housing and cover I provide a floating adjustable rotor case 36 having a cylindrical central opening 38 and within this

2

opening I utilize an impeller or rotor 40 secured on shaft 8 and formed with radial slots 42 to receive the vanes or blades 44.

The lower inner surface 31 of the pump housing or ring 30 is described on a radius the center of which corresponds with the center of the rotor and also with the center of the shaft 8 on which the rotor is mounted, and the lower end 37 of the floating rotor case 36 is formed on a similar radius taken from the same center, wherein the lower end of the case 36 nests against the inner surface of the lower end of the housing 30. The upper inner surface 33 of the housing 30 is formed to represent the upper half of a hexagon and a corresponding surface 35 is provided on the floating case 36 so that the upper end of the case nests in the upper end of the housing with the case 36 in the upper position whereby the inner floating rotor case 36 is rigidly held in both the upper and lower positions.

This rotor is of substantially less diameter than the opening in the case to permit the vertical adjustment of the case with relation to the rotor so that the vanes will be confined and released at opposite sides of the rotor depending upon the eccentric position of the case with relation to the center of the rotor.

To effect adjustment of the case I employ a rod 46 connected with the case and extending through a bracket 48 supported by bolts 50, and a standard 52 is provided for the lever 54 which is pivotally connected to the standard at 56 and to the rod at 58.

Thus with the shaft 8 rotating clockwise and the rotor case raised as seen in Figure 5 the flow of liquid will be from left to right in the port 20 and out the port 22.

However with the rotor case lowered to the position of Figure 7 the direction of rotation of the shaft 8 and the rotor being clockwise, the direction of flow will be reversed or from right to left, in port 22 and out port 20.

Thus by the simple structure above described the direction of flow of a unidirectional pump may be reversed by elevation or lowering of the lever 54 and the case 36 eccentric of the shaft and the rotor. With the case in the position seen in Figure 8, the rotor will be neutral and inoperative to impart movement to the fluid.

Having thus fully described my invention what I claim as new and desire to secure by Letters Patent is:

1. In a rotary pump of the reversible type, the combination which comprises a pump housing

having a pump rotor chamber therein, a rotor in said chamber having blades slidably mounted in radially disposed slots therein, said chamber having parallel vertically disposed sides, a flat upper surface normal to the vertically disposed sides, and having diagonally positioned sides forming the upper side of a hexagon, and the lower side of said chamber being arcuate and formed on a radius from the center of the rotor, a floating rotor case positioned in said rotor chamber and vertically slidably therein, the upper surface of said rotor case having flat surfaces forming part of a hexagon corresponding to and nesting in the upper end of the rotor chamber with the case in the uppermost position, and the lower surface of said rotor case also being arcuate and described on a radius corresponding to the radius of the lower end of the rotor chamber and nested therein with the rotor case in the lowermost position, said rotor case having a cylindrical opening therethrough in which the rotor is positioned, said pump housing having inlet and discharge connections with the inner ends thereof communicating with the pump chamber on opposite sides of the center thereof, a cover plate enclosing said rotor chamber, and means shifting the position of the said rotor case from the exterior of the pump housing.

2. In a rotary pump of the reversible type, the combination which comprises a pump housing having a pump rotor chamber therein, a rotor in said chamber having blades slidably mounted in radially disposed slots therein, said chamber having parallel vertically disposed sides, a flat upper surface normal to the vertically disposed sides, and having diagonally positioned sides forming the upper side of a hexagon, and the lower side of said chamber being arcuate and formed on a radius from the center of the rotor, a floating rotor case positioned in said rotor chamber and vertically slidable therein, the up-

per surface of said rotor case having flat surfaces forming part of a hexagon corresponding to and nesting in the upper end of the rotor chamber with the case in the uppermost position, and the lower surface of said rotor case also being arcuate and described on a radius corresponding to the radius of the lower end of the rotor chamber and nested therein with the rotor case in the lowermost position, said rotor case having a cylindrical opening therethrough in which the rotor is positioned, said pump housing having inlet and discharge connections with the inner ends thereof communicating with the pump chamber on opposite sides of the center thereof, a cover plate enclosing said rotor chamber, a hand lever pivotally mounted on the upper end of the said pump housing, and a rod connecting the said hand lever to the rotor case, said inlet and discharge connections of the pump housing communicating with the rotor chamber through arcuate ports positioned on each side of the vertical center of the pump housing and extending above and below the horizontal center thereof whereby with the rotor case positioned in the upper part of the housing the flow of fluid therethrough will pass in one direction and with the case positioned in the lower part of the housing the direction of flow of the fluid will be reversed.

LON SHANNON.
